2 SHEETS-SHEET 2.

UNITED STATES PATENT OFFICE.

CECIL J. SWAIM, OF MONTREAL, QUEBEC, CANADA.

PAPER-HOLDING ATTACHMENT FOR TYPE-WRITERS.

1,070,636.

Specification of Letters Patent. Patented Aug. 19, 1913.

Application filed December 30, 1911. Serial No. 668,592.

To all whom it may concern:

Be it known that I, CECIL J. SWAIM, a citizen of the United States, residing in the city of Montreal, Province of Quebec, and 5 Dominion of Canada, have invented certain new and useful Improvements in Paper-Holding Attachments for Type-Writers, of which the following is a full, clear, and exact description.

10 This invention relates to improvements in paper holding devices for typewriters, and the main object is to provide a device which may be readily attached to a typewriter and which will carry paper in roll form, thus 15 obviating the necessity of feeding individual sheets into the typewriter at frequent intervals.

A further object is to provide a device holding a plurality of rolls of paper, and 20 provided with one or more ink ribbons whereby copies of the original writing may be made without the use of carbon paper or other copying devices.

To accomplish these objects, I provide a 25 framework pivotally connected to the spindle of the typewriter platen and supported at the rear on a track attached to the typewriter frame. This framework carries a plurality of rolls of paper. The ribbons of 30 paper unwound from the rolls are led collectively around the platen roll of the typewriter in the usual manner. A plurality of ink ribbons are wound on spools carried by the framework and are led across the platen 35 roll in line with the typewriter ribbon. Suitable ribbon shifting and paper holding and cutting mechanisms are provided to complete the device.

In the drawings which illustrate this invention:—Figure 1 is a side elevation of 40 the device showing the method of attachment to a typewriter. Fig. 2 is a partial front elevation of the apparatus, all of the typewriter excepting the platen roll being 45 omitted. Fig. 3 is a detail view of the ribbon shifting mechanism. Fig. 4 is a front elevation of the device.

Referring more particularly to the drawings, 11 designates the framework of a typewriter, 12 the carriage thereof mounted on tracks 13 and carrying a platen roll 14, a paper feed roll 15, and paper guide plate 16.

The paper holding attachment comprises 50 a pair of similar inverted L-shaped side frames 17, one arm 18 of each of which is curved downwardly and is pivotally mount-

ed at its extremity on the spindle 19 carrying the platen roll. The other arm 20 of each frame extends vertically downward a suitable distance. The lower ends of said frames are connected by a horizontal bar 21 60 on which is mounted a suitable carriage 22 having grooved wheels 23 running on a horizontal track 24, supported by arms 25 extending rearwardly from and attached to the frame of the typewriter. The side frames are further connected by bars 26 and 27, the former of which is located at the junction of the arms 18 and 20, and the latter approximately half-way between the 70 bar 26 and the platen spindle 19.

The paper carrying frame proper consists of a pair of similar side members 28 arranged vertically between the side members 17 and supported by the bars 21 and 26. 75 These frames 28 are provided with a plurality of inclined notches 29 in which the spindles 30 of the paper rolls 31 rest.

The ribbon mechanism comprises a small movement frame 32 attached to the arms 18 80 of the frames between the bar 27 and spindle 19. These frames 32 each carry a plurality of ribbon spools 33 to which are attached gears 34 located within the frame 32. These gears 34 are spaced a short distance apart so 85 that they do not mesh, and are driven by pinions 35 located between each pair of gears 34. The purpose of the pinions 35 is obviously to cause all the gears and consequently the ribbon spools to rotate in the 90 same direction. A small crank 36 is attached to one of the pinions to rotate the same. A pawl 37 is pivoted to the movement frame 32 and engages the teeth of the pinion carrying the crank so as to prevent 95 the same rotating in one direction.

A bar 38 extends across the device from frame to frame and carries toward each end thereof the ribbon guide 39. This guide is located in line with the ribbon spools and 100 consists of a strip preferably of metal having the edges doubled over as indicated at 40 so as to inclose the edges of the ribbons passing therethrough. The lower or free end of this guide is folded under on itself, 105 the fold being at an angle of approximately 45°, as shown at 41. In order to prevent a construction of the space between the folded over edge 40 and the guide member, the folded edges are preferably cut at the diagonal fold line. It will be readily understood 110 that the ribbons passing through the guide

will be turned through an angle of 90°, the flat of the ribbon still remaining in the same plane. The ribbons 42 extend from the spools at one side of the device through the 5 guide 39 and across the platen between the same and the typewriter ribbon, and through a guide to the spools at the opposite end of the machine.

In order to readily sever the paper into 10 suitable lengths after the same has been written on, the bar 38 carrying the ribbon guides is provided with a sharp edge 43 at which the paper may be readily torn so as to form a straight and comparatively smooth edge.

15 To prevent paper which has been written on falling forward, a pair of fingers 44 are adjustably mounted on the bar 27 and are each provided with a short pin 45 projecting toward the center of the machine. The fingers 20 44 are adjusted to just clear the edges of the paper, and the pins 45 hold the printed paper up, but by reason of their shortness the paper may be readily disengaged when it is desired to sever any portion thereof.

25 In setting up the machine, the paper ribbons are all led from the rolls over the bar 27 between the fingers 44 thereon, down over the paper guide and around the platen roll 14, the paper passing between the platen roll and the feed roll in the usual manner. The paper is then passed under the cutter bar 38, and if sufficient projects is caught under the pins 45 which will hold the paper up out of the operator's way, thus overcoming 30 the natural tendency of the paper to assume the same curvature which it had in the rolls. Before the paper is passed under the bar 38, care is taken to feed the paper through between the ribbons 42 so that there 35 may be an ink ribbon in engagement with the face of each paper ribbon, the regular typewriter ribbon being in engagement with the face of the outer paper ribbon.

40 In order to shift the ink ribbons 42, the pawl 37 at one end of the machine is thrown up and the spools rotated by turning the crank 36 at the same end of the machine. During this shifting the ribbons rotate the spools at the other end of the machine in 45 the opposite direction so that the teeth of the pinion 35 slip under the pawl 37. When a sufficient shift of the ribbon has been effected, both pawls are let down and the ribbon tightened by turning the crank at the 50 opposite end of the machine in a reverse direction. This tension of the ribbons is necessary to prevent the same being carried away from the printing point by the paper as it passes around the platen roll.

55 60 It will be noted in the drawings that the device is no longer than the typewriter car-

riage, and therefore will not require additional space for operation. The ribbon spools are located with the axes horizontal instead of vertical as is the usual practice, 65 and a great economy of space is thus effected, as the spools and shifting gear are located within the frame work in what would otherwise be waste space.

Having thus described my invention, I 70 declare that what I claim is:

1. A type-writer attachment comprising in combination with the platen roll thereof, a main frame having arms, one end of each of said arms being connected to the platen 75 spindles, upright members having notches therein, supported by the frame, the said notches adapted to accommodate paper carrying roll spindles, a horizontal track supported by the type-writer, wheels on said 80 frame adapted to engage said track, a supplementary frame carried between the arms of the main frame, said supplementary frame supporting ribbon spools, and means for holding the printed paper in a position 85 above the paper being printed.

2. A type-writer attachment comprising a main frame having arms, said arms being connected to the platen spindles of the type-writer, upright members carried by the said 90 main frame, said upright members adapted to support paper carrying rolls, a supplementary frame supported between the arms, ribbon carrying rolls supported in said supplementary frame, gear wheels on the ends 95 of said ribbon carrying rolls, a crank for operating said gearing, and means supported by the frame for supporting the printed paper above the paper being printed.

3. A type-writer attachment comprising 100 in combination, a main frame supporting upright members, paper carrying rolls supported thereby, a track connected with said type-writer, wheels on said main frame adapted to engage said track, arms on said 105 frame, a frame mounted between said arms, said frame supporting ribbon rolls, a gear wheel on one end of each of said rolls, a pinion associated with the gear wheels, and means for operating said pinion to rotate 110 said rolls in one direction, fingers supported by the frame, a laterally extending pin secured to each of said fingers, said fingers adapted to support the printed paper out of 115 engagement with the paper being printed.

In witness whereof I have hereunto set my hand in the presence of two witnesses.

CECIL J. SWAIM.
